UNITED STATES PATENT OFFICE.

CHARLES F. RITCHEL AND GEORGE DOOLITTLE, OF BRIDGEPORT, CONN.,
ASSIGNORS OF ONE-THIRD TO THOMAS B. DOOLITTLE, OF SAME PLACE.

METHOD OF AND APPARATUS FOR TREATING PELTS.

SPECIFICATION forming part of Letters Patent No. 295,050, dated March 11, 1884.

Application filed August 9, 1883. (No model.)

To all whom it may concern:

Be it known that we, CHARLES F. RITCHEL and GEORGE DOOLITTLE, citizens of the United States, residing at Bridgeport, Fairfield county, Connecticut, have invented new and useful Improvements in Method of and Apparatus for Treating Pelts, of which the following is a specification.

Our invention relates to certain new and useful improvements in the method of and apparatus for treating pelts.

It has for its object to successfully remove the "master-hairs" from the pelts in a rapid and uniform manner; and with these objects in view our invention consists in the peculiar method and construction of apparatus herein-after particularly described and specifically claimed.

Prior to our invention, in the treatment of skins, the master-hairs, or, as they are sometimes called, "water-hairs," are either removed by "plucking" or drawing the hairs bodily from the skin, or they are cut or sheared off at a point below the upper surface of the fine hairs or fur. In the latter method it becomes necessary to very nicely adjust the mechanism which is to perform the shearing operation, and it is also necessary to employ a concurrently-operating blast mechanism, in order that the finer hairs or fur shall be blown down out of the path of the cutting-blades. It however frequently happens that, either by failure of perfect adjustment of the co-operating parts of the mechanism or by the peculiar and inherent properties of the skin being operated upon, the extreme points of the finer hairs or fur are also cut, giving to the finished skin a shingled or glazed appearance at such points as have had the natural smoothness of the fur impaired by such accidental clipping. In the former of the two methods alluded to, the pelts have been fed over a supporting-bar or heated tube from the periphery of a rotating cylinder and the master-hairs presented to the action of a pair of gripping-jaws connected to a reciprocating carriage, which latter, after the jaws shall have confined a row of master-hairs between them, is reciprocated so as to make a pull upon the hairs so confined, and thus pluck or pull them

from the skin, this operation being facilitated, as is alleged, by heating the supporting bar or tube. In this last-described apparatus it will be readily seen that there must be some lost time and motion in moving the biting jaws away to pull the hairs and then returning them to their operative position with reference to the skin. In other words, the operation must necessarily be an intermittent one. By our improved method and apparatus all of the seeming difficulties and disadvantages enumerated are effectually overcome and the desired result accomplished expeditiously and effectively, while at the same time the master-hairs removed from the skins are husbanded for use in other arts.

Our invention involves the use of a rapidly-rotating cylinder within a case or chest, the former having a series of slots or hair-inlet ports in its periphery, and the latter a single port or gate, with which the cylinder-ports successively register, and through both of which the long or master hairs are drawn by an exhaust-fan and wind-trunk into a bite between the inside surface of the revolving cylinder and the periphery of a rubber wheel or roll mounted at the end of a stationary hanger and rotated by friction with said cylinder.

In order that others skilled may fully understand our invention, we will proceed to describe in detail the mode and apparatus successfully employed by us, and which forms the subject-matter of our present application, referring by letters to the accompanying drawings, in which—

Figure 1 is a perspective view of one of our improved machines, looking from the rear. Fig. 2 is a side elevation of the interior revolving cylinder with its driving hollow shaft and pulley and the interior supporting stationary shaft. Fig. 3 is a perspective view of the machine looking from the front, and with the face plate or cap of the cylinder case or chest removed. Fig. 4 is a central vertical section of the revolving cylinder and its case, taken at a line passing through the axis of motion, and exposing in elevation the driving-pulley and interior stationary shaft with the vertical frame and rubber gripping-wheel employed to coact with the revolving cylinder; and Fig. 5 is a

transverse section of the revolving cylinder, showing the character of the series of gates or openings in its periphery.

Similar letters indicate like parts in the several figures.

A represents the tripod supports of the bed-plate or frame B, upon which latter is mounted a fixed support or bearing-block, in the opposite ends of which the stationary horizontal shaft D has its bearings, as already seen at A', A", Fig. 1. The front end of the shaft D passes through a tube or sleeve, E, in the bearing A", said tube or sleeve being furnished with a circular flange, F, secured by bolts G to the head or back disk H of the revolving cylinder I, the rear end of the tube or sleeve E being keyed to a driving-pulley, J, by which rotary motion is imparted to the cylinder I. The cylinder I is incased or closed by a chest or jacket, K, the front L of which is bolted in place, as clearly shown at a, Figs. 1, 3, and 4. This chest or jacket K is rigidly connected or secured to the bed-plate or frame of the machine, and the cylinder I is rapidly rotated within said case or chest. Suitably connected with the frame is an exhaust-fan arranged within a fan-case, M, which latter is connected with the front L of the cylinder-case by a wind-trunk, N, made in sections, so as to permit of separation, as clearly shown at Fig. 3. The fan-case M is furnished with an exit-trunk, O, through which the plucked hairs escape, as will be hereinafter explained. The exhaust wind-trunk N, as will be seen at Fig. 3, is connected with the front L of the case K at or above the center, so that the current produced by the exhaust-fan will be in an upward direction, as indicated by the arrows at Fig. 3. The cylinder I has its periphery penetrated by a series of gates or slots, b, forming inlet-ports for the hairs and the air-currents, as will be presently explained. Depending from the end of the fixed shaft D (which, passing through the rear of the cylinder-case, projects therein, as clearly shown at Fig. 3) is a hanger or arm, P, in the lower end of which is pivoted a rubber cylinder or roll, Q, adapted to be compressed against the interior surface of the revolving cylinder I, so that all hairs penetrating or extending through the ports b shall be quickly gripped between the inside surface of the short bridges c, (see Fig. 5,) between the ports b and the periphery of the rubber cylinder or roll, the bite of which is of sufficient duration to enable the rotary movement of the cylinder I to extract the master-hairs by their roots. It should of course be understood that the cylinder case or chest K has an opening, d, Fig. 4, at its bottom, but is tight at all other points, so that by the action of the fan a current is established in the direction described and indicated, so as to draw the hairs into the bite of the roll Q.

R is the skin-support, which is hinged at e at the rear end, and its front end supported on the top of a vertical rod, S, passing up

through a sleeve, f, at the upper ends of supporting-rods T T. The lower end of the rod S is connected by a quick thread with a revolving plate, U, which is adapted to be rotated by the operative, and thus bring the support R into proper relation with the cylinder-chest K or the opening d therein.

The skin to be operated is drawn over the support R with the fur side upward, and as the master-hairs come into alignment with the gate or port d in the case K, the vacuum induced therein by the exhaust-fan causes the hair to rise up through the gate d and pass also through the successive ports b of the revolving cylinder I and into the bite of the rubber roll Q, which is rotated by its frictional contact with the interior of the cylinder, and as the latter continues to revolve while the bite of the roll Q also continues, the hairs are plucked or pulled from the skin at a very rapid rate, and are, after being released from the bite of roll Q, taken by the exhaust and delivered through the wind-trunk O to any suitable wire cage or receptacle, from which they may be removed and sold to hatters or others. It will be observed that the ports b in the periphery of the revolving cylinder I have each a straight side and a beveled side, we having found that this construction facilitates the passage of the hairs into the bite of the rubber roll and the successful plucking of said hairs.

We have shown and described the cylinder-chest as connected near the center with the exhaust apparatus, and have found that this arrangement produces satisfactory results; but the exhaust may of course occur from some suitable point in the periphery of the cylinder-chest; or it might be made centrally through the supporting-shaft D. We do not wish to be confined to the exact details of construction described, as they may be varied considerably without departing from the spirit of our invention.

In passing the skin over the supporting-bar R it becomes necessary to let go of the edge of the skin a short time before the completion of the operation, and to avoid the tendency which would be thus induced of the edge of the skin being drawn bodily toward or into the gate d, we arrange on the outside of the cylinder-case, on each side of the said gate, guard-plates V, hinged or pivoted at their upper ends, and extending downward in a curved direction sufficiently far to have their lower ends rest upon the upper surface of the support R. Between these guard-plates and the cylinder-case are arranged in any suitable manner springs, which tend to hold the lower ends of the plates V in contact with the support, and thus serve to hold the skin at a proper distance from the gate d.

W is a scraper or guard-plate, arranged to impinge on one side of the rubber roll Q and between it and the inside of the cylinder I, which serves to keep the plucked hairs from

returning to the ports in the cylinder, and to scrape off any hairs which might otherwise adhere to the rubber roll.

We desire to call particular attention to the fact that in the employment both of our method and apparatus the master-hairs of pelts are brought by the action of an air-current toward and within the bite of the plucking mechanism, which action is the reverse of that resulting in the employment of a blast toward the skin and away from the plucking mechanism referred to hereinbefore as one of the existing methods in use. In such last-named method the blast is employed to drive the fur close to the skin and leave the hair standing, requiring, as will be seen, a very nice adjustment of the blast, while with us the current is toward the plucking mechanism and away from the skin, so that it is immaterial whether such current is obtained by an exhaust or blast, though for simplicity of structure we prefer securing it by exhaust, and it will thus be understood that while we have shown what we believe to be the best means of plucking—viz., a rotary mechanism—still that feature of our invention relating to the proper direction of the hairs toward the plucking mechanism can be advantageously employed in a machine having a plucking mechanism differing in character and construction from that shown and described by us; hence we do not propose to be limited in this particular.

We have found in practice that with a machine in which the cylinder I has a diameter of about twelve inches, with ports one and three-fourths inch long, we have been enabled to make about fourteen thousand pulls or plucks per minute; but we do not, of course, propose confining ourselves to any given proportion.

What we claim as new, and desire to secure by Letters Patent, is—

1. In a machine for treating pelts, the combination of a support over which the skin may be drawn, a vacuum-chest, K, provided interiorly with a revolving plucking-cylinder, I, having a series of ports, b, in the periphery thereof, through which the ends of the master-hairs are drawn, a rubber or other flexible roll, Q, hung in the end of a stationary hanger, and arranged to impinge against and be driven by frictional contact with the cylinder I, means for driving the cylinder, and an exhaust-fan connected with the vacuum-chest K, substantially as and for the purpose set forth.

2. The combination and arrangement of the cylinder I, arranged within the vacuum-chest K, and connected by bolts or otherwise with the flanged end of a sleeve, E, provided with a driving-pulley, J, the central stationary shaft, D, extending within the chest K, hanger P, and rubber roll Q, substantially as and for the purpose set forth.

3. In combination with the support R and vacuum-chest K, the guard-plates V, for controlling the skin after the removal of the band, substantially as hereinbefore set forth.

4. In combination with the vacuum-chest K, cylinder I, and roll Q, the stripper or guard-plate W, substantially as and for the purposes set forth.

5. The revolving cylinder I, provided with a series of ports, b, having one side of each beveled, substantially as and for the purpose set forth.

6. The supporting-bar R, having its rear end hinged to the frame of the machine and its front end resting upon a vertically-adjustable rod, S, substantially as and for the purpose set forth.

7. The rod S, connected at its lower end to a revolving plate, V, by a quick screw-thread, and adapted to be raised and lowered by the rotation of the plate V, substantially as and for the purpose set forth.

8. The combination and arrangement of the supports A, plate B, bed C, bearings A' A'', shaft D, sleeve E, flange F, cylinder I, pulley J, vacuum-chest K, hanger P, roll Q, exhaust-fan, and trunks N O, substantially as shown and described.

9. The cylinder I, provided with inlet-ports in its periphery for the reception of the master-hairs, and adapted to be rotated to pull said hairs, substantially as hereinbefore set forth.

10. The method of properly presenting the master-hairs of pelts to the action of plucking mechanism, which consists in the employment of an air-current toward the plucking mechanism, and placing the pelt within the influence of said current, whereby the hairs are caused to travel toward and within the bite of the plucking mechanism, substantially as hereinbefore set forth.

11. The method of plucking pelts, consisting in placing the same within the influence of an air-current toward the plucking mechanism, then grasping said hairs thus presented and pulling the same bodily from the skin, substantially as hereinbefore set forth.

12. The method of plucking pelts, consisting in placing them within the influence of an air-current toward the rotary plucking mechanism arranged within an exhaust or vacuum case, drawing said hairs out by rotary action, and discharging the same into a suitable cage or receptacle, substantially as hereinbefore set forth.

In testimony whereof we have hereunto set our hands in the presence of two subscribing witnesses.
